J. L. GRANT

CLOTHES WASHING ATTACHMENT FOR VEHICLES

Filed Nov. 2, 1925

UNITED STATES PATENT OFFICE.

JOSEPH L. GRANT, OF CHICAGO, ILLINOIS.

CLOTHES-WASHING ATTACHMENT FOR VEHICLES.

Application filed November 2, 1925. Serial No. 66,380.

My invention relates to improvements in clothes washing attachments for vehicles, and it consists in the combinations, constructions, and arrangements herein described and claimed.

An object of my invention is to provide a device which may be carried on a vehicle, such as an automobile, and which, when filled with clothes and suitable washing fluid, such as soap and water, will cause the thorough washing of the clothes through the motion given to the device by the movement of the vehicle over the road.

A further object of my invention is to provide a simple washing device of the type described, which can be readily attached to or removed from a vehicle, and which is so arranged as to have an oscillatory movement to throw the clothes and the wash water first toward one end and then the other of the washing device.

A further object is to provide a device of the type described, in which the means for holding the cover on also comprises a compensating means for normally keeping the device in a horizontal position, but which will give readily to permit it to tilt, so as to cause the movement of the wash water back and forth.

Other objects and advantages will appear in the following specification, and the novel features of the invention will be particularly pointed out in the appended claims.

My invention is illustrated in the accompanying drawings, forming part of this application, in which—

Figure 1 is a side view of the device as applied to the running board of an automobile.

Figure 2 is an enlarged section substantially along the line 2—2 of Figure 3,

Figure 3 is an end view of the device with the spring removed, certain portions being shown in section, and

Figure 4 is a fragmentary section through the casing at right angles to the section shown in Figure 2.

In carrying out my invention, I provide a casing consisting of a box-like portion 4, which is preferably made of metal, such as pressed steel, but which may be made of any suitable material. In order to strengthen the device, I preferably provide a rolled bead 5 at the upper edges, this bead having a stiffening wire disposed therein. The box or casing, as shown in the drawings, is pref-

erably oblong, and has at each end an L-shaped flange 7 projecting inwardly, the purpose of this flange being explained later. The bottom and the sides of the box are 60 provided with corrugated sheets 8, along which the clothes are designed to move in the washing operation.

On the underside of the casing is a rounded hollow trunnion 9, which is preferably 65 made of a semi-cylindrical piece of metal having flanges 10 by means of which it is secured to the bottom. The semi-cylindrical portion 9 has openings for permitting the entrance of stop pins 11 carried by a base 70 portion 12. These openings are slightly larger than the pins, so as to permit the oscillation of the casing on the trunnion. The base is preferably a wooden or metal 75 plate. It is provided with resilient cushions or stops 13 underneath the ends of the casing. Clamps 14 are used to secure the base to the running board 15. The clamps are provided with screws 16 which hold the base firmly in position.

The cover 17 has a flange 18 arranged to enter the upper portion of the box so as to permit the cover to rest on the bead 5. At each end of the cover is an extension 19 having an opening through which a hook 20, attached to a spring 21, may enter, the opposite end of the spring being secured to an eye 22 carried by the base.

From the foregoing description of the 90 various parts of the device, the operation thereof may be readily understood. Normally, as stated, the base is held on by the clamps 14. By loosening the hooks 20, the casing may be immediately lifted from the stop pins 11, and the cover removed, and the 95 casing filled with clothes and with water containing soap or other wash ingredients.

When the cover is placed and the casing is placed on the stop pins, the hooks 20 may be attached, and the casing is counterbalanced so as to remain substantially in a horizontal 100 position when the vehicle is at rest. This is due to the springs 21, whose compensating

action is such that when the vehicle is in motion, it will oscillate on the hollow trunnion 9, and will cause the water, together with the clothes, to rush toward one end and then toward the other, as the vehicle proceeds. The flanges 7 tend to break the force of the water, so as to prevent it from splashing out at the ends. The springs, it will be 105 observed, have a double function, for they

hold the cover securely in position, and, at the same time, counterbalance the device, so that it will oscillate easily in either direction by the movement of the automobile over the road. The stops 13 tend to cushion the force of the oscillating casing as it moves downwardly at the ends.

While I have shown the interior of the casing as being of the arrangement specified, 10 it is obvious that other interior arrangements might be made, without departing from the spirit and the scope of the invention.

I claim:

1. The combination with a vibratory member, of a base plate secured to said member, 15 trunnion pins carried by said base plate, a casing, a hollow trunnion carried by the bottom of the casing and having openings arranged to receive said pins, whereby the 20 casing is adapted to oscillate about said pins, a cover for said casing, and springs having one of their ends attached to the base plate and their other ends attached to the cover for holding the latter to the casing, and for

counterbalancing the casing in a normally 25 horizontal position.

2. A clothes washing attachment comprising a casing, means for pivotally mounting the casing for oscillation about a central axis, a cover and means attached to the cover 30 for holding the latter on the casing and for counterbalancing the casing in a normally horizontal position.

3. A washing device comprising a base, spaced apart aligned trunnion pins carried 35 by said base, a casing having a hollow trunnion extending transversely along the bottom thereof and having openings arranged to receive said pins, a cover for the casing having extensions at the ends thereof, counterbalancing springs secured to said base and adapted to be secured to the extensions of the cover for holding the casing normally in a parallel position with respect to the base, and cushion members carried by the base 40 for cushioning the impact of the casing when the latter is tilted on its trunnion.

JOSEPH L. GRANT.
